UNITED STATES PATENT OFFICE.

LEON C. GERMAIN, OF CONWAY, AND ALDERIC G. GERMAIN AND CHARLES E. PARSONS, OF GREENFIELD, MASSACHUSETTS.

DIE.

Application filed March 24, 1923. Serial No. 627,433.

To all whom it may concern:

Be it known that we, LEON C. GERMAIN, ALDERIC G. GERMAIN, and CHARLES E. PARSONS, citizens of the United States, residing 5 at Conway, Greenfield, and Greenfield, respectively, in the county of Franklin and State of Massachusetts, have invented certain new and useful Improvements in Dies, of which the following is a specification.

10 This invention relates to dies for cutting screw-threads, and methods of making the same.

An object of the invention is the provision 15 of a die in which the cutting threads are arranged at an angle to the axis of the die, whereby a shearing cut is obtained.

A further object is the provision of a die having inclined clearance holes relieved at each side to feed the cut material from the 20 die.

A further object is the provision of a die which may be reversed and operated with either face toward the work.

In constructing the die, the clearance 25 holes are first drilled in a blank of metal at equal distances from the center. The center hole is then drilled and tapped out, and the threads cut therein. The clearance holes are finished to provide a relief, consisting 30 of a relatively flat surface adjacent the cutting threads, which feeds the cut metal outwardly and prevents clogging of the die.

In the accompanying drawings, we have shown several embodiments of the invention. In this showing:

Figure 1 is a plan view of one form,

Figure 2 is a transverse sectional view on line 2—2 of Figure 1,

Figure 3 is a side elevation showing the 40 die in use,

Figure 4 is a plan view of another form of the invention,

Figure 5 is a transverse sectional view on line 5—5 of Figure 4,

Figure 6 is a side elevation showing the 45 die in use,

Figure 7 is a plan view of a two-piece die, and,

Figure 8 is a side elevation of the same.

50 Referring to Figures 1 to 3 of the drawings, the die consists of a blank 1, which may be circular as shown, or may be formed in any desired shape. In this instance, we have shown a one-piece die, but it will be apparent that the invention applies, to two-

piece dies as well. In forming the die, a plurality of clearance holes 2 are drilled in the stock at equal distances from the center and equally spaced from each other. As shown, these clearance holes are arranged at 60 an angle to the axis of the die. A center hole 3 is then cut in the blank and threads 4 tapped on the surface of this hole. The threads are finished by cutting back the upper edge at a point where the work is first 65 engaged, as indicated at 5, and cutting back the lower edge at a point at the opposite side, as indicated at 6, to provide a cutting point which first engages the work. Referring to Figure 2 of the drawings, it 70 will be noted that the edge 7 of the threads is at an incline, caused by the intersection of the center hole 3, and the clearance holes 2. This causes the lower thread to engage first in cutting and the remaining threads to engage in turn. This provides a shearing cut, 75 as distinguished from the present type of cut where all of the threads of a die engage at the same time. If the die is turned over, it will be apparent that the working edge of 80 the threads will be reversed and the proper clearance will also be obtained, providing a cutting point at the bottom where the tool first engages and a recess at the top.

After the threads have been cut, the clearance holes are then relieved by slightly flattening the side walls, as at 8, adjacent the point where the clearance hole intersects the center hole. The advantage of this relief will be apparent from an inspection of Figure 9 of the drawings. In this figure, we have shown a bolt 9 having threads 10 cut thereon. By providing the inclined clearance holes with substantially flat surfaces adjacent the point where the metal is being 95 cut, the metal is fed outwardly, as indicated at 11. This prevents the accumulation of short pieces of metal or chips in the clearance holes, which tend to strip the threads when the die is removed.

In Figures 4 to 6 of the drawings, we have shown a die 12 substantially the same as that shown in Figures 1 to 3. In this instance, however, the clearance holes 13 are inclined in the opposite direction. As shown in Figure 6 of the drawings, this causes the cut pieces of metal 14 to be projected in the opposite direction toward the work 15.

In Figures 7 and 8 of the drawings, we have shown a die formed of a rectangular 110

blank 16. The clearance holes 17 arranged on opposite sides of the die intersect the edge, as indicated at 18, and divide the blank into two sections. Similar clearance holes 19 are arranged between the clearance holes 17. By forming a die in this manner, all the advantages of the ordinary two-part die are obtained and the shearing cut and delivery of cut metal, described in connection with Figures 1 to 6 of the drawings, also results.

Dies heretofore used have been referred to as self-clearing dies, but as a matter of fact, the cut metal passes into the clearance holes at such an angle that it strikes against the walls of the clearance holes and is broken off into relatively short pieces. As the die is oiled, these short pieces form a soggy mass, which fills the clearance holes. In removing the die from the work, some of these chips frequently fall into the cut threads and as the die passes over them, the formed thread is destroyed. By providing the inclined clearance holes, and cutting the threads with a shearing cut, the strips formed by the cutting operation resemble the cut metal delivered from a lathe in cutting threads by lathe tools and these strips pass into the clearance holes at such an angle that they are readily delivered in a direction parallel to the axis of the die. This eliminates the possibility of the pieces of cut

metal breaking off and filling the clearance holes.

It is to be understood that the forms of the invention herewith shown and described are to be taken as preferred examples of the same, and that various changes in the shape, size, and arrangement of parts may be resorted to without departing from the spirit of the invention or the scope of the subjoined claim.

Having thus described our invention, we claim:

A die provided with a central opening and a plurality of clearance openings intersecting therewith and having their axes disposed at an inclination to that of said central opening, whereby a plurality of substantially spirally disposed lands are provided, and threads provided on said lands, the threads adjacent one face of the die being relieved on one side of the land and the threads adjacent the other face of the die being relieved on the opposite side of the land, whereby each land has cutting edges on one side at one end and on the other side at the opposite end.

In testimony whereof, we affix our signatures.

LEON C. GERMAIN.
ALDERIC G. GERMAIN.
CHARLES E. PARSONS.
